UNITED STATES PATENT OFFICE.

HERBERT JOHN RUSHTON, OF SOUTHFIELDS, ENGLAND.

MEANS FOR SUPPORTING CERAMIC WARE WHILE BEING FIRED IN OVENS.

1,313,018.

Specification of Letters Patent.

Patented Aug. 12, 1919.

Application filed November 10, 1917. Serial No. 201,304.

To all whom it may concern:

Be it known that I, HERBERT JOHN RUSHTON, a subject of the King of Great Britain and Ireland, residing at Southfields, in the county of Surrey, England, have invented Improvements in or Relating to Means for Supporting Ceramic Ware While Being Fired in Ovens, of which the following is a specification.

10 This invention has reference to the means used for supporting dishes, saucers, tiles and other articles of ceramic ware during the process of firing them in glost.

15 An object of the invention is the provision of ware-supporting means that shall be considerably less in weight than the generally adopted fireclay boxes or saggars, so as to contribute to fuel economy by greatly increasing the relative weight of the ware, 20 which constitutes productive firing.

25 A further object of the invention is the provision of supporting means so constructed and arranged that the pieces of ware can be readily placed in position and examined, and any of them found to be defective or in 30 poor condition can be readily removed and replaced by another piece or other pieces of ware without disturbing the remaining pieces.

35 For these purposes, ware-supporting means according to the invention embodies a holder or support of fireclay or other refractory material comprising a base or bottom plate carrying end walls but no side walls. Such a holder or support is herein-after called the ware holder. When the 40 ware to be fired is not self-supporting, the upper ends of the end walls of the ware holder are provided with recesses or slots

45 to receive and support the ends of one or more longitudinal bars provided, or each provided along its length with a number of pins or projections, (hereinafter referred to as pins), the bar or each bar with its pins being also usually made of fireclay or other refractory material. The pins on the bar, or each bar, are arranged to hold pieces of ware in a more or less vertical position and some of them, namely those adjacent to the 50 end walls, also serve to hold the bar in place and prevent endwise motion thereof and of the pieces of ware supported in position by the pins or projections thereon. On the base or bottom plate of the ware-holder 55 may be laid longitudinal supporting rods,

preferably of triangular shape in cross section, for the pieces of ware that are not self-supporting to rest on. The ware holder will usually be provided with only one upper longitudinal bar with a set of holding pins 60 but for some kinds of ware two or more such bars may be used.

Two or more ware-holders such as described may be adapted to be superposed one on the other and when the ware is self-supporting, that is to say each article can rest on its own bottom, the bar with pins can be dispensed with.

The invention will now be more particularly described with reference to the accompanying drawings illustrative of apparatus embodying it. In these drawings, Figure 1 is a conventional perspective view, and Figs. 2 and 3 are respectively a longitudinal view and a transverse sectional view of one 70 form of supporting means according to the invention. Figs. 4 and 5 show respectively in plan and vertical section, and to a larger scale than Figs. 1, 2, and 3, a portion of the said ware supporting means. Fig. 6 is a 80 view analogous to Fig. 5, but illustrating a slightly modified construction. Figs. 7 and 8 are views similar to Figs. 1, and 2 respectively, but illustrating the use of alternative means for supporting and separating 85 the ware. Fig. 9 is a perspective view to a larger scale than Figs. 7 and 8, of one of the thimbles shown in Fig. 8. Figs. 10 and 11 are detail sectional views of portions of the ware support shown in Figs. 1 and 7. 90 Fig. 12 is a perspective representation of a modified form of supports according to the invention, adapted to be superposed and carried one on the other.

The construction illustrated in Figs. 1 to 95 5 inclusive, comprises a ware-holder made of fireclay or other refractory material and comprising a base or bottom plate 1 carrying end walls 2 the upper ends of which are provided with recesses or slots 3 to receive 100 and support the ends of an upper longitudinal bar 4, the said ware-holder being open at its sides so as to enable ware to be readily inserted in it and removed therefrom. This bar is provided along its length with a 105 number of pins 5, the bar with its pins being also made of fireclay or other refractory material. The bar 4 is perforated along its length and the pins 5 are made removable therefrom and of any desired length so that 110

they can be easily removed and changed for others of a different length, to suit the particular pieces of ware A to be fired. The bar 4 can be readily placed in the recesses 5 or slots 3 in the top of the end walls 2, thus enabling the ware-holder to be quickly adapted for use. The bar 4 may be flat, as shown, or of other stronger section and the holes therein be vertical as shown in Figs. 1 and 10 2 so that the pins 5 extending therethrough will also be vertical. Or the holes may be inclined to the vertical, as shown in Fig. 6, so that the pins 5 will also be inclined to the vertical in order the better to support some 15 articles of ware. In this case the upper side of the bar may be provided with a number of flat surfaces 7 arranged at right angles to the holes to support the heads of the pins. The ware-holder and bar and pins 20 may, in cases designed for use in sufficiently low temperatures, be of metal in lieu of fireclay or other highly refractory material.

In some cases the bar may, as shown in Figs. 7 and 8, be constituted by a row of 25 the well known potters' thimbles 9 adapted at its ends to be carried on the end walls 2 of the ware-holder. In this case spurs 10 on the thimbles serve as the pins or projections to hold the ware in position. Fig. 9 30 shows one of the thimbles 9 separately. The bottom of the base plate 1, in order to enable it to stand firmly on an uneven or irregular surface, is provided with three short legs or lugs two of which, namely 11, are 35 arranged at or near opposite sides of the base plate 1 at one end thereof and the other, namely 12 is arranged centrally at the opposite end of the plate 1.

When ware-holders of the kind referred 40 to are to be used singly, the end walls 2 may be of triangular shape as shown in Figs. 1 and 2 and in Figs. 7 and 8, to minimize weight and, for the same reason, they may be made thin and provided with flanges 13 45 at the sides and bottom.

When it is desired to use two or more ware-holders of the kind referred to one above the other, the end walls may be made of square or rectangular shape as shown in 50 Fig. 12 so as to provide bearing surfaces 14 and 15 on the end walls of a lower ware-holder for the feet or lugs 11 and 12 of an upper one to rest upon. In this case, the two feet or lugs 11 at one end of an upper 55 ware-holder can rest directly at 14 upon the upper surfaces of one of the end walls of the lower ware-holder at opposite sides of the recess or slot 3 therein for carrying one end of the longitudinal bar 4 of the lower 60 ware-holder. The central foot or lug 12 at the other end of the upper ware-holder may rest upon the smoothly finished prepared surface or seat 15 formed in the top of the other end wall of the lower ware-holder 65 above the slot 3 extending through such end

wall below the seat 15 for carrying the other end of the longitudinal bar. The central foot or lug 12 has a smooth lower surface and may bear upon one or more rollers or 70 balls of refractory material, or upon a bed of sand or other granular material, placed upon the smoothly finished prepared surface or seat 15 on the lower ware-holder. When a number of ware-holders are thus placed one upon another as described, then, 75 during the process of heating up, the more rapid expansion of any individual ware-holder is readily provided for by the sliding movement of the yielding surface separated by the rollers, balls, or the granular material, thus reducing to a minimum, injurious 80 stresses which would otherwise be set up in the ware-holders. In the same way, the ware-holders are permitted to move relatively to one another when being subjected 85 to the process of cooling, during which period more or less unequal contraction takes place between them. Thus, by assisting the unavoidable expansion and contraction due to heating up and subsequent cooling, the life 90 of a ware-holder constructed according to the invention is considerably prolonged and wastage and repair reduced.

The ware A shown in Figs. 2, 3 and 8 is supported at its upper edges by the pins 5, 95 or the spurs 10, and at its lower edges by saddles 17 of the cross section shown in Fig. 11.

Ware-holders of the same or of very similar construction to that shown in Fig. 12 100 may also be used without the bar and pin attachment, or the thimbles for carrying jugs, teapots, cups, vases and the numerous other varieties of ware of a self-supporting character. When the object in view is 105 merely to carry self-supporting ware, the form of the ware-holder may be simplified by the omission of the slots 3 or like arrangements for the support of a horizontal bar with pins or a row of thimbles with projections, but the form of ware-holder shown in Fig. 12 is generally preferable, as it has a more extended range of utility, while the parts 11, 12, 14, 15 retain their advantage of providing for freedom of movement during 110 expansion and contraction.

Ware-holders according to the invention are more particularly adapted for use in muffle ovens and ovens of the Dressler type 120 wherein the products of combustion of the heating medium do not come into contact with the goods being fired. Ovens of the Dressler type are described in the specifications of Conrad Dressler's United States Patents Nos. 1,023,628, 1,116,036, 1,193,245 125 and 1,170,428.

What I claim is:—

1. For supporting ceramic ware during firing, an open-sided ware-holder comprising 130 a rectangular base and end walls, said base

being provided on its lower side at one end with a central foot or lug and at its other end with a pair of laterally arranged feet or lugs.

5. For supporting ceramic ware during firing, a plurality of superposed open-sided ware-holders each comprising a base and end walls, the base of each ware-holder being provided on its lower side at one end with 70 a central foot or lug and at its other end with a pair of laterally arranged feet or lugs and the upper ends of the end walls of each ware-holder being provided with bearing surfaces adapted to support the 10 feet or lugs on the superposed ware-holder and admit of their moving longitudinally thereon.

3. For supporting ceramic ware during firing, superposable ware-holders of refractory material each comprising a base provided on its lower face at one end with a central foot or lug and at its other end with a pair of laterally arranged feet or lugs and a pair of rectangular end walls carried by 20 said base, one of these end walls being provided on its upper face or edge with a pair of bearing surfaces for the lateral feet or lugs of a superposed holder, and the other of the said end walls being provided at the 25 central portion of its upper face or edge with a bearing surface for the central foot or lug of the superposed holder.

4. For supporting ceramic ware during firing, an open-sided ware-holder comprising a rectangular base and end walls the upper ends of which are adapted to carry a longitudinal ware-supporting member, said base being provided on its lower side at one end with a central foot or lug and at its 30 other end with a pair of laterally arranged feet or lugs.

5. For supporting ceramic ware during firing, an open-sided ware-holder comprising a rectangular base and end walls the upper ends of which are formed with bearings 45 adapted to support a longitudinal ware-supporting member and retain it in place laterally, said base being provided on its lower side at one end with a central foot or lug and at its other end with a pair of laterally arranged feet or lugs.

6. For supporting ceramic ware during firing, an open-sided ware-holder of refractory material comprising a rectangular base 55 and end walls carried by said base, and a longitudinal bar supported at its ends by said end walls and provided along its length with a number of downwardly extending ware pins or projections, said base being provided on its lower side at one end with a central foot or lug and at its other end with a pair of laterally arranged feet or lugs.

7. For supporting ceramic ware during firing, an open-sided ware-holder of refractory material comprising a rectangular base 60

and end walls carried by said base, a longitudinal bar supported at its ends by said end walls and provided along its length with a number of perforations, and downwardly extending ware-supporting pins inserted in 70 said perforations, said base being provided on its lower side at one end with a central foot or lug and at its other end with a pair of laterally arranged feet or lugs.

8. For supporting ceramic ware during 75 firing, an open-sided ware-holder of refractory material comprising a rectangular base and end walls carried by said base, a longitudinal bar supported at its ends by said end walls and provided along its length with a 80 number of perforations, and downwardly extending ware-supporting pins differing in length inserted in said perforations, said base being provided on its lower side at one end with a central foot or lug and at its 85 other end with a pair of laterally arranged feet or lugs.

9. For supporting ceramic ware during firing, an open-sided ware-holder of refractory material comprising a rectangular base 90 and end walls carried by said base, a longitudinal bar supported at its ends by said end walls and provided along its length with a number of downwardly extending ware pins or projections and saddles arranged on 95 said base, said base being provided on its lower side at one end with a central foot or lug and at its other end with a pair of laterally arranged feet or lugs.

10. For supporting ceramic ware during 100 firing, an open-sided ware-holder of refractory material comprising a rectangular base and end walls carried by said base and provided at their upper ends with bearings, a longitudinal bar supported at its ends in 105 said bearings and provided along its length with a number of inclined perforations, and upon its upper side with a number of surfaces inclined at right angles to the perforations, and headed pins extending through 110 the perforations in positions inclined to the longitudinal bar, said inclined surfaces serving to support the heads of the pins, said base being provided on its lower side at one end with a central foot or lug and at its 115 other end with a pair of laterally arranged feet or lugs.

11. For supporting ceramic ware during firing, an open-sided ware-holder of refractory material comprising a rectangular base 125 provided on its lower face at one end with a central foot or lug and at its other end with a pair of laterally arranged feet or lugs and end walls carried by said base and provided at their upper ends below their end surfaces with bearings adapted to carry a longitudinal bar provided along its length with downwardly extending pins, said base being provided on its lower side at one end with a central foot or lug and at its other

end with a pair of laterally arranged feet or lugs.

12. For supporting ceramic ware during firing, superposable open-sided ware-holders of refractory material each comprising a base furnished on its lower face at one end with a central foot or lug and at its other end with a pair of terminal feet or lugs, and end walls carried by said base and provided at their upper ends with slotted bearings and a longitudinal bar supported at its ends in said slotted bearings and provided along its length with downwardly extending pins,

one of the said end walls of each ware holder being provided on its upper face or edge 15 with a pair of bearing surfaces for the lateral feet or lugs of a superposed ware-holder and the other end wall of said ware-holder being provided at the central portion of its upper face or edge with a bearing surface 20 for the central foot or lug of the said superposed holder.

Signed at London, England, this fifteenth day of October, 1917.

HERBERT JOHN RUSHTON.
